(57) **CLAIM**

The ornamental design for a solar floating fountain, as shown and described.

DESCRIPTION

FIG.1 is a first perspective view of a solar floating fountain showing my new design;

FIG.2 is a second perspective view thereof;

FIG.3 is a front view thereof;

FIG.4 is a back view thereof;

FIG.5 is a left side view thereof;

FIG.6 is a right side view thereof;

FIG.7 is a top view thereof; and,

FIG.8 is a bottom view thereof;

The broken lines and all areas within depict portions of the solar floating fountain that form no part of the claimed design.
